UNITED STATES PATENT OFFICE.

JOHN HEAPS BIRCH, OF GATLIFF, KENTUCKY.

INCANDESCENT ELECTRIC LAMP.

1,150,738.

Specification of Letters Patent. Patented Aug. 17, 1915.

Application filed August 8, 1913. Serial No. 783,750.

To all whom it may concern:

Be it known that I, JOHN HEAPS BIRCH, a citizen of the United States, residing at Gatliff, in the county of Whitley and State 5 of Kentucky, have invented new and useful Improvements in Incandescent Electric Lamps, of which the following is a specification.

This invention relates to improvements in 10 illuminating devices, and it has for its primary objects to provide an incandescent electric lamp of improved construction embodying a plurality of filaments which are connected in parallel to the terminals and 15 are preferably circular and arranged concentrically one within another, and to provide an improved bulb to inclose the filaments, said bulb forming a reflector at the rear and a lens at the front thereof, the 20 bulb being also shaped so that it will fit readily into lamps as commonly used on locomotives, automobiles, street cars or other vehicles, and a plug may be located at different positions on the bulb whereby 25 the bulb can be supported by a lamp socket whether the same be arranged horizontally or vertically and electric current thereby supplied to the filaments.

A lamp of this character will have a relatively high candle power and hence may be 30 used advantageously as a substitute for arc lamps as heretofore used for head-lights, and the construction of the filaments is such that they will continue to give light even 35 though one or more of the filaments or portions thereof may become broken or burned out.

To these and other ends, the invention 40 consists in certain improvements, and combinations and arrangements of parts, all as will be hereinafter more fully described, the novel features being pointed out particularly in the claims at the end of the specification.

45 In the accompanying drawing:—Figure 1 is a front elevation showing one embodiment of a lamp constructed in accordance with the present invention; Fig. 2 represents a central vertical section of the lamp 50 as shown in Fig. 1; Fig. 3 is a view similar to Fig. 2 showing the terminal and supporting plug arranged in a different position.

55 Similar parts are designated by the same reference characters in the several views.

Illuminating devices embodying the pres-

ent invention are capable of use for illuminating purposes in general, but they are particularly adapted for use in those cases where a high power light is required such, 60 for example, as on head-lights of locomotives, automobiles, street cars and other vehicles. The device embodies a bulb 1 composed preferably of an integral glass structure, the front being shaped to form a lens 65 or bull's-eye 2 and the rear is concave and may be silvered or otherwise treated to form a reflector 3. The present invention provides an electric lamp of improved construction which is positioned behind the lens 2 70 and in proper relation to the focus of the reflector 3. In its preferred construction, a plurality of incandescent electric filaments 4 are used which are circular in form and of different diameters, these circular filaments 75 being arranged concentrically and one positioned within another. These filaments are so connected to the lamp terminals that they will receive the electric current in parallel. In the construction shown, the filaments are 80 connected at diametrically opposite points to a pair of terminal wires 5 and 6, these terminal wires being rigidly supported within the bulb by the lamp base 7 and they are electrically connected to the threaded sleeve 85 8 and center contact 9 respectively. That portion of the lamp base which projects to the exterior of the bulb is adapted to fit into a correspondingly formed socket arranged in the casing which is to contain the lamp 90 or illuminating device. Obviously, bases and sockets of different kinds can be used. It will also be understood that the base of the lamp bulb can be located at different positions on the bulb to meet the requirements 95 and different conditions. For example, while in Figs. 1 and 2, the base is shown at the bottom of the bulb, this base can be arranged at the rear of the lamp and in center of the reflector, the latter construction 100 adapting the lamp to sockets which are arranged horizontally. An incandescent electric lamp embodying a plurality of filaments which are connected in parallel to the terminals not only concentrates a high candle power within a small space, but will continue to give light even though one or more of the filaments may become broken or burned out. Also, should one half of any 105 one of the filaments become broken or burned out, the remaining half of this filament will continue to burn. The bulb which

incloses the filaments is preferably of heavy glass and sealed after having the air withdrawn therefrom as is the case with ordinary incandescent electric lamps.

5 I claim as my invention:—

1. An incandescent electric lamp comprising a bulb composed of glass, the rear portion of which forms a concave reflector, a plurality of concentric filaments of graduated sizes, and terminals connected in parallel to said filaments and supporting them in coöperative relation with the reflector.
- 10 2. An incandescent electric lamp comprising a bulb, the rear portion of which is provided with a concave reflector, a plurality of filaments of graduated sizes arranged concentrically of one another and with respect to said reflector, and terminals connected in parallel to said filaments and supporting them in coöperative relation with the reflector.
- 15 3. An incandescent electric lamp comprising a bulb having a concave reflector at the rear thereof, and a plurality of circular filaments arranged concentrically with one another and said reflector, the inner filament of smallest diameter being located closer to
- 20
- 25

the reflector than the outer filament of largest diameter.

4. An incandescent electric lamp comprising a bulb having a concave reflector at the rear thereof, a set of endless circular filaments arranged concentrically with one another and said reflector and occupying different planes in front of the reflector, and terminals connected to said filaments at diametrically opposite points and supporting the filaments.

5. An incandescent electric lamp comprising a bulb having a concave reflector at the rear and a lens at the front thereof, a set of endless circular filaments arranged concentrically with one another and said reflector and lens, and terminals connected to said filaments at diametrically opposite points and supporting the filaments.

In testimony whereof I have hereunto set my hand in presence of two subscribing witnesses.

JOHN HEAPS BIRCH.
